RECREATION APPARATUS

Charles B. Poorman, Jr., Schuylkill Haven, Pa.

Application November 29, 1946, Serial No. 713,044

6 Claims. (Cl. 104—81)

1

The present invention relates to recreation apparatus, more particularly to a form of swing involving a compound to-and-fro motion.

In a conventional type of swing, an oscillatory motion is produced in a radial direction about fixed pivotal points. The swinging motion thus produced does not include any gliding component.

It is an object of the present invention to provide a recreation apparatus which combines not only an oscillatory motion but also a longitudinal gliding motion which results in a compound swaying to-and-fro motion, thus giving increased exhilaration to the user of the apparatus.

Another object is the provision of a form of swing having a compound motion, the components of which may be resolved independently into a radial swinging motion and an arcuate longitudinal gliding motion.

A special object of the invention is the provision of a form of swing, the attraction for which is enhanced by virtue of a to-and-fro motion of a compound order.

Other objects of the invention will manifest themselves as the description proceeds.

For a full and more complete understanding of the invention, reference may be had to the following description and accompanying drawing, wherein:

Figure 1 is a perspective view of recreation apparatus constructed in accordance with the present invention;

Figure 2 is a longitudinal section through one of the tracks supporting the swing; and

Figure 3 is a transverse section through the tracks, showing the trolley mounting of the swing seat.

Referring to Figure 1 of the drawing, it will be seen that the recreation apparatus herein contemplated may comprise a framework consisting of a pair of parallel longitudinal curved track members 1, preferably of pressed steel. The members 1 are formed in a smooth or regular curve formed from a segment of a circle and may be supported in an elevated position by two pairs of upright end supports 2, 3, and 4, 5 respectively. The supports 2, 3, 4, and 5 are connected along their ground ends by a rectangular frame or base consisting of longitudinal braces 6 and 7 and transverse braces 8 and 9. Top cross braces 11 and 12 connect with the track members 1.

The track members 1 may be box-shaped, as shown particularly in Figures 2 and 3, and are of substantial length so as to provide a relatively long longitudinal gliding motion for the swing, designated generally by the numeral 13. It will

2

be noted that the track members 1 are mounted on their supporting frame so that their curvature is upwardly with respect to their length. Each of the track members 1 is provided with a slot 14 running longitudinally thereof, said slot being designed to permit the protrusion therethrough of links 15. One end of each of the links 15 is connected to a trolley, indicated generally by the reference character 16. Each of the trolleys 16 is provided with four wheels which may have either roller or ball bearings. The width of the trolley 16 is such that it is freely accommodated within the box-shaped channel of the track members 1, and at the same time prevent any binding or friction between the links 15 and the edges of the slots 14. To facilitate this arrangement, it is preferable that the link be rigidly secured to the base plate 17 of the trolley.

On the inside of each end of the tracks 1, there is mounted a compression spring 20, one end of which is secured to a closure or end plate 21, which retains said spring in a fixed position. The free end of the spring 20 is provided with a buffer 22 which may be of rubber or the like. The construction just described functions as a resilient stop when the trolley 16 strikes thereagainst, and also imparts a momentum in the reverse direction of the swing at the peak or high point thereof. This arrangement functions in the nature of a catapult for increasing the downward momentum of the swing at the point where the direction of oscillation is reversed, which feature is herein-after elaborated upon more fully.

The swing proper is designated by the reference character 25, and may comprise a seat 26 provided with side pieces 27. The pieces 27 have apertures through which rings 28 may be inserted and to which rings one end of swing lines 29 of rope or other flexible material may be fastened. The other end of the swing lines 29 is similarly fastened to rings 30, which in turn are held in apertures provided at the lower end of the links 15.

In using the swing, the following explanation will be helpful in appreciating the function of the foregoing structural features. As in the case of the conventional swing, the to-and-fro motion is developed by the body exertions of the occupant. These exertions create a momentum which gradually builds up or increases in proportion to a degree roughly depending upon the strenuousness of said exertions, and this momentum is first translated or converted into an oscillatory motion of the to-and-fro type.

During the process or period of developing this

oscillatory motion, an incipient longitudinal gliding motion is simultaneously initiated and/or developed within the trolley 16, from which the swing 13 is suspended. The oscillatory motion and the gliding motion, although separate and independent of each other, combine to produce a compound motion which becomes manifest as in embodying a gliding and a swinging movement to the swing, producing in the occupant the sensation of gliding and swinging, both at the same time.

It will be noted that the amplitude of the two components producing this compound or double motion increases concurrently until a maximum is reached. In the case of the gliding motion, this occurs when the trolley 16 glides to the respective ends of the tracks 1 and encounters the buffer 22. This does not take place, however, until the conclusion or end of a continuous, relatively long glide in either a forward or backward direction.

At the end of the gliding motion, the oscillatory motion will have substantially reached its peak, and the momentum of the swing 13 is then reversed. By virtue of the buffer 22 placing the spring 20 under compression by arresting the upward movement of the trolley 16, a catapultic force is created, which functions to accelerate the reverse or downward momentum of the swing as the reverse direction thereof starts.

From the foregoing description, it is obvious that in utilizing the present swing construction, an added enjoyment results from imparting a continuous long gliding motion to the usual swinging or oscillatory motion. Although these two motions are compounded, they may be resolved into separate independent components which may be regarded in the nature of a safety factor. That is to say, the extent or degree of the several motions depends upon the momentum developed through the exertions of the person swinging, which exertions are of a body and leg action. Consequently, in the case of a child, these actions are relatively limited to the size of the child, and those of a small child are comparatively of little magnitude. In such instances, the gliding motion will not be developed to an extensive degree, and therefore will not constitute a possible source of hazard or danger to a small occupant. On the other hand, as the user of the swing becomes more adult, the compounding of the oscillatory and gliding motions is less likely to be dangerous and produces a thrill not obtained in a conventional form of swing.

It is obvious that certain modifications of my invention, as illustrated, will occur to those skilled in the art; for example the length of the tracks 1, as well as their degree of curvature, may be changed. The longer and more gradual the gliding motion, the longer will be the period of oscillation; on the other hand, the shorter and more abrupt the curvature of the tracks, the faster will be the to-and-fro motion of the swing. As a general guidance, it may be stated that if the peaks of the oscillatory and the gliding motions are roughly synchronized, the swinging action will be coordinated to produce maximum enjoyment, and, therefore, the apparatus should preferably be constructed with that view in mind.

It is my desire and intention to include all such modifications as may be provided in putting the invention into practice within the purview of the appended claims.

What is claimed is:

1. In recreation apparatus of the character described, a pair of suspended trackways, each de-

fining a segment of a large circle, a pair of independent trolley devices, one operating in each of said trackways, a pair of flexible lines, one attached to each trolley device, and a seat suspended between the two lines.

2. A free-swinging recreational swing comprising a pair of suspended trackways, each defining a segment of a large circle, a pair of independent trolley devices, one operating in each of said trackways, a pair of flexible lines, one attached to each trolley device, and a seat suspended between the two lines.

3. A free-swinging recreational swing comprising a pair of suspended trackways, each defining a segment of a large circle, a pair of independent trolley devices, one operating in each of said trackways, a pair of flexible lines, one attached to each trolley device, a seat suspended between the two lines, and spring means located at the end of each trackway and adapted to contact the trolleys near the end of said trackways.

4. A free-swinging recreational swing comprising a frame structure including upright supports, a pair of suspended trackways, each defining a segment of a large circle, a pair of independent trolley devices, one operating in each of said trackways, a pair of flexible lines, one attached to each trolley device, and a seat suspended between the two lines.

5. A free-swinging recreational swing comprising a pair of suspended trackways, each defining a segment of a large circle, and comprising curved, hollow beam members substantially square in cross section, a pair of independent trolley devices, one operating in each of said trackways, each trolley device including a plurality of wheels and a downwardly projecting link member projecting through a slot formed longitudinally of and on the outer periphery of each of said trackways, a pair of flexible lines, one attached to each trolley device link, and a seat suspended between the two lines.

6. A free-swinging recreational swing comprising a pair of suspended trackways, each defining a segment of a large circle, and comprising curved, hollow beam members substantially square in cross section, a pair of independent trolley devices, one operating in each of said trackways, each trolley device including a plurality of wheels and a downwardly projecting link member projecting through a slot formed longitudinally of and on the outer periphery of each of said trackways, a pair of flexible lines, one attached to each trolley device link, a seat suspended between the two lines, and buffer means at each end of each trackway comprising a coil spring adapted to impart to the trolley a catapultic action at the beginning of a downward movement of the swing in a reverse direction.
